UNITED STATES PATENT OFFICE.

BENJAMIN S. LA FLEUR, OF HAVERHILL, MASSACHUSETTS, ASSIGNOR TO THE REECE BUTTON HOLE MACHINE COMPANY, OF BOSTON, MASSACHUSETTS, A CORPORATION OF MAINE.

MACHINE FOR ROUGH-ROUNDING AND LASTING STITCHED-DOWN SHOES.

1,398,524.

Specification of Letters Patent. Patented Nov. 29, 1921.

Application filed October 13, 1920. Serial No. 416,605.

To all whom it may concern:

Be it known that I, BENJAMIN S. LA FLEUR, a citizen of the United States, and resident of Haverhill, county of Middlesex, State of Massachusetts, have invented an Improvement in Machines for Rough-Rounding and Lasting Stitched-Down Shoes, of which the following description, in connection with the accompanying drawing, is a specification, like characters on the drawing representing like parts.

This invention has for its object to provide a novel machine for simultaneously rough rounding and lasting stitched-down shoes, thus performing at one operation the lasting of the upper and the trimming of the sole.

Features of the invention consist in means to force the upper into the angle between the side of the last and the projecting margin of the sole, means for pressing the marginal portions of the upper and sole together thereby to perform the lasting operation, and means operating simultaneously to trim the edge of the sole at the required distance from the last.

In the present machine the shoe being operated on is held against a work supporting element which also functions to tuck the upper into the corner between the last and the sole, and the trimming knife is so arranged and supported that it operates while the marginal portions of the sole and upper are clamped between the presser element and the work supporting element.

Other features of my invention relate to various improvements in machines of this class all as will be more fully hereinafter set forth.

In order to give an understanding of my invention, I have illustrated in the drawings a selected embodiment thereof, which will be now described, after which the novel features will be pointed out in the appended claims.

In the drawings, Figure 1 is a side view of a machine embodying my invention.

Fig. 2 is a front view thereof.

Fig. 3 is a top plan view.

Fig. 4 is a section on the line 4—4, Fig. 1.

Fig. 5 is a section on the line 5—5, Fig. 3.

Fig. 6 is a section on the line 6—6, Fig. 3.

The principal parts of the device comprise a work supporting member or work-guiding

member against which the projecting portion of the sole of the shoe is held and which also operates to force the upper into the angle between the side of the last and the projecting margin of the sole, a presser element or beater constructed to act on the under face of the sole at the margin sole and press or beat the marginal portions of the sole and upper portions together, and a trimming knife which operates to trim or rough round the sole.

These parts are suitably mounted upon a frame 5 which may have any suitable shape adapted for this purpose.

The work-holding or work-guiding device comprises a plate 6 secured to the frame 5 and a member 10 in the form of a truncated cone which overlies the plate 6 and cooperates therewith to support and guide the shoe and which also by its shape operates to force the upper into the angle between the side of the last and the projecting portion of the sole. In Figs. 1 and 6 I have shown a portion of a shoe on a last, 1 indicating the last, 2 the upper of the shoe, 3 the sole thereof and 4 the marginal portion of the upper which is to be stitched to the marginal portion of the sole. In operating on a shoe the latter is held, as shown in Figs. 1 and 6 with the portion thereof projecting beyond the last placed against the work-holding device, and the operator will move the shoe relative to the work holder so that the latter will follow around the last and in doing so the work is pressed against the member 10.

Situated beneath the member 10 is a presser element or beater 7 which is reciprocated vertically and which cooperates with the elements 6 and 10 to press together the marginal portions of the upper and the sole. The trimming knife, by which the sole is trimmed, is indicated at 33 and this is also arranged to have a reciprocating movement.

The beater or presser member 7 is yieldingly mounted on a slide or carriage 8 which is slidable vertically on ways 9 formed on the frame 5. This slide 8 is shown as having the dove-tail ways 29 formed therein and the beater or presser member 7 is provided with an extension 28 which slides in the ways 29. Said extension has a hub 49 through which extends an adjusting screw 30, that is screw threaded into the lower end of the carriage 28. Said screw has a hand

wheel 31 on its lower end and a spring 32 encircles the screw 30 and is confined between the hub 49 and the hand wheel. Said spring thus makes a yielding support for the 5 presser member 7. The slide or carriage 8 is reciprocated vertically on the ways 9 and for this purpose said slide 8 is provided with rack teeth 23 which mesh with teeth 22 formed on one end of a lever 20 pivoted 10 to the frame at 21, the other end of said lever 20 being connected by a link 19 to a crank pin 18 carried by a shaft 15 which is rotatively mounted in the frame. Said shaft is shown as having fast and loose 15 pulleys 16, 17 thereon by which it may be driven.

The presser member 7 is preferably so adjusted by the screw 30 that when the slide 8 is raised the presser member will engage the 20 under side of the sole before said slide reaches the upper limit of its movement, so that during the final upward movement of the slide the spring 32 will be compressed thus producing a yielding pressure against 25 the sole.

The trimming knife 33, by which the sole is trimmed, is secured to the slide 8 and by such upward movement of the slide the trimming knife cuts through the sole, thereby 30 trimming the latter, the plate 6 constituting a cutting bed against which the knife acts.

In Figs. 1 and 2 the slide is shown as raised and the beater 7 is pressing against the sole and the cutter 33 has cut through 35 the edge of the sole. When the slide is at the lower limit of its movement the expanding action of the spring 32 will raise the presser member 7 relative to the knife so that the face of said presser member will be above 40 the cutting edge of the knife. When the carriage 8 moves upwardly therefore, the presser member 7 is first brought against the bottom of the sole and as the carriage continues its upward movement the spring 45 32 is compressed and the knife is brought into position to cut through the sole and trim the latter, as shown in Fig. 1. As the shoe is moved around the work support, 6, 10, the member 10 forces the upper into the 50 corner between the side of the last and the projecting portion of the sole, the beater or presser member 7 presses the marginal portions of the sole and upper together and the cutter trims the sole, thus performing the 55 rough rounding operation.

It will be noted that when the cutter comes into action the marginal portions of the sole and upper are clamped between the work support and the presser member 7 so that 60 the shoe will be firmly held during each cutting operation.

In the present embodiment of the invention the member 10 is shown as having a reciprocating motion parallel to the sole. This 65 is accomplished by mounting the member 10

on a slide 11 which is provided on its under side with dove-tailed ways 12 which receive the guiding member 13 formed on the frame 5. Said slide 11 is connected by a link 24 to a crank pin 25 carried on the end of a 70 shaft 26 which extends parallel to the shaft 15 and is geared thereto by suitable gearing 27, which is constructed so that the two shafts 26 and 15 rotate at the same speed.

The member 10 is provided on its under 75 face with a recess to receive the plate 6, said recess being sufficiently larger than the plate to permit the necessary reciprocating movement of the member 10 relative to the plate. This member 10 is in the form of a truncated 80 cone and is freely rotatable in the slide.

I claim:

1. In a machine of the class described, the combination with means for supporting on one of its sides an edge portion of a sole of a 85 shoe, of means for pressing the marginal portions of the sole and upper together and means for trimming the sole.

2. In a machine of the class described, the combination with means for supporting on one of its sides an edge portion of a sole of a 90 shoe, and tucking the upper into the angle between the side of the last and the sole, of means for beating together the marginal portions of the sole and upper, and means 95 for trimming the sole.

3. In a machine of the class described, the combination with means to force the upper of a shoe into the angle between the side of the last and the projecting margin of the 100 sole, means for pressing together the marginal portions of the sole and upper, and means for trimming the sole.

4. In a machine of the class described, the combination with means to force the upper of a stitched-down shoe into the angle between the side of the last and the projecting margin of the sole, of a reciprocating presser element coöperating with said means to press the upper against said margin of the sole, 110 and means to trim the sole.

5. In a machine for lasting stitched-down shoes, the combination with means to draw progressively the upper firmly around the last and to beat the edge of the upper against 115 the edge of the sole, of means to trim the edge of the sole progressively.

6. In a machine for lasting stitched-down shoes, the combination with a work-guiding member, of a presser member movable toward and from said work-guiding member to press together the edge of the upper and the edge of the sole, a lasting tool to draw the upper close about the last, and means to trim the edge of the sole simultaneously 125 with the pressing movement of the presser member.

7. In a machine for lasting stitched-down shoes, the combination with a work-guiding member, of a presser member movable to- 130

- ward and from said work-guiding member to press together the edge of the upper and the edge of the sole, a lasting tool to draw the upper about the last, and a trimming 5 knife associated with the presser member for trimming the edge of the sole.
8. In a machine for lasting stitched-down shoes, the combination with a work-guiding member in the form of a plate, of a presser 10 member movable toward and from the work-guiding member to press together the edge of the upper and the edge of the sole, a circular lasting tool having a recess to receive the work-guiding member, and means to reciprocate the presser and lasting tool in 15 timed relation and in directions at right angles to each other.
9. In a machine of the class described, the combination with means to force the upper 20 of a stitched-down shoe into the angle between the side of the last and the projecting margin of the sole, of a reciprocating presser element coöperating with said means to beat the upper against said margin of the sole, 25 and a knife associated with the presser element to trim the sole.
10. In a machine of the class described, the combination with means to force the upper 30 of a stitched-down shoe into the angle between the side of the last and the projecting margin of the sole, of a reciprocating presser element coöperating with said means to beat the upper against said margin of the sole, and a knife constructed to trim the sole while 35 the beater is in engagement therewith.
11. In a machine of the class described, the combination with means to force the upper 40 of a shoe into the angle between the side of the last and the projecting margin of the sole, of means for pressing together the marginal portions of the sole and upper, and means to trim the sole while said marginal portions are thus pressed together.
12. In a machine of the class described, the combination with a work support for one 45 side of the edge portion of a stitched-down shoe which projects beyond the upper at the side of the shoe, of a presser element to press or beat together the projecting portions of the sole and upper, a knife to trim the sole, 50 and means to give the presser element its pressing movement and subsequently to give the knife its cutting movement.
13. In a machine of the class described, the combination with a frame, of a work support carried thereby, and adapted to engage the top face of the projecting marginal portion of the sole and upper of a stitched-down shoe, a reciprocating slide mounted on said frame to move in a direction at right angles 55 to the operative face of said work support, a trimming knife carried by said slide, a presser element yieldingly supported by said slide, and means to reciprocate the slide toward and from the work support. 60
14. In a machine of the class described, the combination with a frame, of a work support carried thereby and adapted to engage the top face of the projecting marginal portion of the sole and upper of a stitched-down 70 shoe, a reciprocating slide mounted on said frame to move in a direction at right angles to the operative face of said work support, a trimming knife carried by said slide, a presser element yieldingly supported by said 75 slide, and normally occupying a position above the cutting edge of the knife, and means to reciprocate the slide whereby through the upward movement of the slide the presser is first brought against the sole 80 of the shoe and then the knife is moved into position to trim the sole.

In testimony whereof, I have signed my name to this specification.

BENJAMIN S. LA FLEUR.
